ALFRED WEILAND, OF PHILADELPHIA, PENNSYLVANIA.

CARBURETER FOR INTERNAL-COMBUSTION ENGINES.

1,276,842.

Specification of Letters Patent. Patented Aug. 27, 1918.

Application filed April 4, 1917. Serial No. 159,603.

To all whom it may concern:

Be it known that I, ALFRED WEILAND, a citizen of the United States, residing at Philadelphia, in the county of Philadelphia and State of Pennsylvania, have invented 5 a certain new and useful Improvement in Carbureters for Internal-Combustion Engines, of which the following is a specification.

10 The present invention relates generally to a carbureter for internal combustion engines and more specifically to the feeding of fuel to the main reservoir of the carbureter and to the control and mixing of the 15 liquid fuel and air as discharged to the motor intake.

It is an object of the invention to provide 20 means for automatically supplying liquid fuel to the main reservoir of the carbureter, such means embodying an auxiliary or supplemental fuel feeding mechanism, which, under normal conditions, remains inactive and inoperative but which is at all times in condition to supply liquid fuel to the main 25 fuel reservoir in case the main fuel feeding means, through one cause or another, becomes inoperative. In the carbureter of my present invention, the pressure conditions existing in the motor intake are relied upon to produce sufficient vacuum in a 30 supply reservoir to lift the liquid fuel from a low level source and in case the vacuum produced is too low for this purpose, a condition may arise where the carbureter is 35 temporarily, at least, without liquid fuel, and it is therefore the object of my invention to provide a means which is automatically operable under the conditions stated to supply liquid fuel to the main reservoir 40 until such a time as the vacuum is again built up to cause the regular feeding to be again resumed.

It is a further object of the invention to provide means under the positive control of 45 the throttle valve for definitely proportioning the liquid fuel and air so that the motor receives a proper and efficient mixture for the condition under which the throttle is adjusted.

50 For the purpose of illustrating my invention, I have shown in the accompanying drawings one form thereof, which is at present preferred by me, since the same has been found in practice to give satisfactory 55 and reliable results, although it is to be understood that the various instrumentalities

of which my invention consists can be variously arranged and organized and that my invention is not limited to the precise arrangement and organization of the instrumentalities as herein shown and described. 60

Referring to the drawings:

Figure 1 represents a sectional elevation of a carbureter embodying my invention, the same being taken on line 2—2 of Fig. 2. 65

Fig. 2 represents a plan of the same.

Fig. 3 represents a section on line 3—3 of Fig. 1.

1 designates the casing of the carbureter which is provided with a removable cover 70 or top 2 by means of which access is had to the interior of the carbureter for purposes of repair or otherwise, as will be understood. In the present instance, the casing 1 is so constructed as to form a carbureting chamber 3, a main fuel reservoir 4, a storing reservoir 5 and an auxiliary reservoir 6. The latter has communication by way of the overflow outlet pipe 7 with the reserve tank 8 which has direct connection 75 and communication with a source of low level liquid supply (not shown) through the pipe 9. The carbureting chamber 3 communicates with the atmosphere through the main air inlet passage 10 and discharges 80 into the motor intake by way of the outlet 11 which is, of course, subject to the pressure conditions existing in the aforesaid motor intake. 85

As here shown the carbureter nozzle or 90 mixture jet is formed in a part of the throttle valve controlling means and is located substantially transversely of the chamber 3 so that when the throttle is open, the air entering by way of the passage 10 95 and traversing the chamber 3 is divided and passes to opposite sides of the nozzle structure. Referring to Fig. 3, 12 designates the throttle valve which is suitably shaped and located to cut off the carbureting chamber 100 3 from the motor intake as desired and in the present instance this valve is formed with a central sleeve 13 which is fixed to the tubular stem 14 of the throttle valve operating means. The stem 14 has a relatively 105 long bearing in the carbureter casing 1 and projects therefrom at the top where it has the throttle lever 15 attached and by which it is operated as required. This stem 14 is further provided with an intermediate body 110 portion 16 which serves as a guide bearing for the tubular plunger 17 and also pro-

vides the hollow extension 18 arranged concentrically of the plunger 17 and terminating at a point below the normal liquid fuel level. In this connection, it will be noted 5 that a plurality of openings 19 are provided in the said extension at substantially the normal level line of the liquid fuel and serve to permit air to escape from the interior of the extension and carry liquid fuel 10 to the jet outlets 20. These outlets 20 are formed respectively at opposite sides of the throttle valve 12 and communicate with the space 21 between the extension 18 and the sleeve plug 22 which is threaded into the 15 casing 1 in axial alinement with the stem 14 whereby in assembled condition the two parts are in telescoped relation and from the aforesaid space 21 which communicates with the jet reservoir 23 formed in the body portion 20 of the plug 22. Fuel from the main reservoir 4 is supplied to the jet reservoir 23 by way of the passage 24 and inlet port 25.

26 designates a needle valve for controlling the supply of liquid fuel to the mixture nozzle and in the present instance this valve is connected to the lower end of the tubular plunger 17, so that as the said plunger moves in one direction or the other, the valve 26 is correspondingly shifted. In the present construction, this plunger extends through the stem 14 and is provided with a head, such as the nut 27 or the like, which is adapted to be engaged by a pivoted lever 30 under the control of the throttle valve operating mechanism. The lever 28 is preferably of bifurcated or forked construction and carries at its outer or free end a cam roller 29 which rides upon the cam surface 35 formed as a part of the lever 15. A suitable spring 31 is employed to maintain the roller 29 in proper relation with its coacting cam surface. From the foregoing, it will be evident that as the cam/lever 15 is 40 rotated to either open or close the throttle, its movement will be transmitted to the pivoted lever 28 and raise or lower the latter and thus move the needle valve 26 according to requirements. It will be noted that a 45 port 32 is provided in the plunger 17 for the passage of air from the interior of the said plunger to the jet chamber 23 and that it is preferably below the normal liquid level or at least the level under starting and slow 50 speed conditions so that the air drawn through is relatively saturated with liquid fuel.

Referring now to the main reservoir 1 for liquid fuel, 33 designates an air vent suitably formed in the casing 1 and communicating with the said reservoir above the normal liquid level whereby the liquid fuel is supplied by gravity action to the jet as will be understood. 34 designates an outlet leading from the storing reservoir 5 to the main

reservoir 4 and having its mouth normally below the fuel level, so that the outlet is liquid sealed and the liquid from the storing reservoir 5 gradually replaces the liquid used from the main reservoir 4 through the 70 action of the air bubbling or rising through the liquid sealed outlet 34.

35 designates the outlet from the auxiliary chamber 6 to the storing reservoir 5, this outlet, in the present instance, terminating well within the chamber 5 and having its mouth normally sealed by the stored liquid fuel. A valve 36 is arranged to control the opening and closing of the outlet 35 and for this purpose is provided with a reciprocal stem 37 which is connected to a lever 38 which carries a float 39 and has its fulcrum 40 intermediate the two points of connection, so that when the float rises the valve 36 is lowered and vice versa. The 85 auxiliary chamber 6 is adapted to be subjected to the pressure conditions in the motor intake and to that end the casing wall is provided with an opening 41, the opening and closing of which is controlled by the 90 movement of the stem 14 and as here shown, the said stem is angularly grooved as shown at 42 to form a passage or connecting conduit with a port 43 which communicates by way of the channel 44 with the motor intake. 95 Thus in one position of the throttle, the groove 42 will provide a full size communicating passage between the ports 41 and 43 and in another position of the throttle this communicating passage will be reduced in 100 area to a proportionate extent both with the end in view of maintaining a substantially constant vacuum within the chamber 6.

45 designates a passage forming a communication between the reserve tank 8 and a float chamber 51 as a means of by-passing liquid around the chamber 6 under certain conditions. This passage 45 is provided with a valve seat 46 with which the valve 47 cooperates and this latter is suitably connected for movement with a float 48 in the said chamber 51. Under all normal conditions of operation, that is, with an operative supply of liquid fuel in the main reservoir 4 the float 48 is held in such a position that 115 the valve 47 closes the passage 45 and the feeding of the carburetor takes place by way of the auxiliary reservoir 6 as will be explained. Thus the tank 8 is normally subject to sufficient vacuum from the motor intake to be filled from the low level supply and since the pipe 7 is of relatively considerable length, there will be at all times, under normal operation, a supply of liquid fuel in the tank 8, the level of which is approximately at the end of the pipe 7. The continued action of the vacuum causes the liquid to overflow and run through the pipe 7 into the storing or auxiliary reservoir 6 where it is controlled by the float 39 and valve 36. 130

In case the suction from the motor intake should for any reason be insufficient to draw fuel into the tank 8, and in view of this condition (which necessarily must be a temporary condition), the main reservoir as well as the storing and auxiliary reservoirs 5 and 6 become exhausted, the level in the chamber 51 will lower and thus cause the float 48 to drop and the valve 47 to open. 10 This permits the stored liquid fuel in the tank 8 to discharge into the chamber 51 and act as an auxiliary supply until conditions return to normal.

Referring now to the throttle structure 15 and its adjuncts, it will be noted that the throttle valve is substantially of hollow or tubular construction at its central portion and within which the parts are so arranged and coördinated as to form not only the main 20 fuel jet of the carburetor but also an auxiliary reservoir embodying air and fuel supply to form an auxiliary jet which is particularly advantageous for starting or slow speed conditions. Assuming these latter 25 conditions to exist and the throttle to be in its closed position, the fuel assumes a level in the chamber 23 substantially co-incident with the two ports 19 and since at this time also but one of the outlets 20 is directly sub-30 ject to the suction of the motor intake, the other outlet 20 becomes an inlet for air from the main air opening 10. Thus under a starting condition, air is drawn through the inlet 20 into contact with the liquid fuel 35 and discharges through the outlet 20 to the motor intake while a second body of air is drawn through the plunger 17 and passes by way of the port 32 beneath the level of the fluid and bubbles its way to the outlet 20, 40 so that the resulting combined mixture is a saturated mixture well adapted for the requirements of starting or slow speed work. Under running conditions of the motor, the 45 throttle jet becomes less of an auxiliary or priming device, since it is then transformed into the main fuel jet and with the throttle open, the suction is generally sufficient to practically empty the chamber 23 of any surplus liquid fuel and the carbureting chamber 50 draws directly upon the main fuel reservoir for its supply.

In the present instance, I have provided a regulating device operating as an adjunct of the throttle valve whereby the needle valve 55 26 is adjusted according to the position of the throttle valve as determined by load or speed conditions. Thus, as the throttle is opened, the cam 30, through the lever 28, lifts the plunger 17 and causes the needle 60 valve to open a distance proportionate to the opening of the throttle valve so that there is a definite amount of fuel supplied to mix with the air. The operation of the main fuel feed to the reservoir 4 is substantially 65 a continuous one since the lowering of the

level in the reservoir 4 breaks or tends to break the liquid seal of the outlet 34, thus permitting air to bubble in to the storing reservoir 5 and replace the liquid which naturally flows out. The liquid in the storing reservoir 5 is replaced by the opening of the valve 36 whenever the float 39 rises sufficiently, as will be understood. The liquid fuel is supplied substantially continuously to the reservoir 6 owing to the minus pressure 75 from the motor intake which causes an overflow from the tank 8 through the pipe 7.

In connection with the grooved portion 42 of the stem, it will be understood that its function is to maintain the vacuum produced 80 by the motor intake relatively constant under general operating conditions. Conditions of operation, however, are varied and consequently this statement as to constant vacuum is subject to exceptions, such for instance, as a load or speed condition where the motor intake minus pressure approaches a plus pressure, when the vacuum may be insufficient to draw liquid fuel into the tank 8 and consequently the overflow to reservoir 90 6 is discontinued. In such a situation, the carburetor may still perform its function so long as the reservoirs 4, 5 and 6 contain fuel and after the liquid level in the main reservoir 4 has lowered there is still the 95 reserve fuel in tank 8 to be drawn upon when the valve 47 opens. Thus the reserve tank 8, by-pass conduit 45 and float controlled valve 46 afford a supply in the nature of a safety factor, which operates and may be depended 100 upon to meet adverse conditions of low vacuum and insure operation until normal conditions are restored.

In order to overcome the possible tendency for the continued feeding of fuel to the main reservoir by way of the by-pass after it is once brought into operation and thus prevent an automatic return to the normal feeding, I have preferred to sub-divide the main reservoir 4 by the partition 49 which as here shown is a continuation of one wall of the storing reservoir 5. An opening 50 in this wall provides a communication between the float chamber 51 and the main reservoir 4 and this opening is preferably in close proximity to the normal level in the storing tank 5. The opening being so located is substantially at the normal float line of the float 48 so that the lowering of the liquid below this opening insures the opening of the valve 47 and hence the fuel feed by way of the by-pass 45 passes from the chamber 51 through the opening 50 to the main reservoir 4. When vacuum conditions are such that the normal feed is restored, the incoming fuel flows into the chamber 51 considerably faster than it flows out, and consequently, the float 48 rises, closes the valve 47 and as soon as the level in the auxiliary reservoir 6 has risen sufficiently to 130

open the valve 36, conditions return to normal and the by-pass feed becomes temporarily inoperative.

It will now be apparent that I have devised a novel and useful construction which embodies the features of advantage enumerated as desirable in the statement of the invention and the above description and while I have in the present instance shown and described, the preferred embodiment thereof which has been found in practice to give satisfactory and reliable results, it is to be understood that the same is susceptible of modification in various particulars without departing from the spirit or scope of the invention or sacrificing any of its advantages.

What I claim is:

1. In a carbureter, a casing forming a main reservoir and a carbureting chamber, a fuel jet supplied from said main reservoir, means to automatically replenish the fuel supply in said main reservoir, an auxiliary fuel replenishing means for said main reservoir, said auxiliary means being inoperative under normal conditions, and means to automatically bring said auxiliary replenishing means into operation under abnormal conditions.

2. In a carbureter, a casing forming a main reservoir and a carbureting chamber, a fuel jet supplied from said main reservoir, means controlled by pressure conditions in the motor intake for replenishing the fuel supply in said main reservoir, and a by-pass fuel feed to said main reservoir controlled by the liquid level in said main reservoir.

3. In a carbureter, a main fuel reservoir, a supply reservoir having a liquid sealed outlet to said main reservoir, means rendered operative by the breaking of said seal to supply liquid fuel to said main reservoir, automatic means to normally replenish said supply reservoir, and an auxiliary fuel feed to said main reservoir independent of said normally operative replenishing means.

4. In a carbureter, a main fuel reservoir having an air vent above the normal liquid level, a storing reservoir having an outlet below the normal level in said main reservoir forming a liquid seal, an auxiliary reservoir having an outlet to said storing reservoir, a valve for said last named outlet, a float in said auxiliary reservoir connected to said valve for opening and closing it according to level conditions, means to automatically replenish said auxiliary fuel reservoir from a low level source, and an auxiliary fuel feed for said main reservoir automatically operable in place of said float controlled valve.

5. In a carbureter, a casing forming a main reservoir, an auxiliary reservoir and a carbureting chamber, a fuel jet supplied from said main reservoir, a receiving tank

having free communication with said auxiliary reservoir, means to subject said auxiliary reservoir to the pressure conditions in the motor intake, means to feed said main reservoir from said auxiliary reservoir, means to retain a predetermined supply of liquid fuel in said tank and an automatically controlled by-pass feed from said tank, to said main reservoir.

6. In a carbureter, a casing forming a main reservoir, an auxiliary reservoir and a carbureting chamber, a fuel jet supplied from said main reservoir, a receiving tank, means forming an unobstructed conduit between said auxiliary reservoir and a point in said receiving tank above a predetermined liquid level, means to subject said auxiliary reservoir to the pressure conditions in the motor intake, means to feed said main reservoir from said auxiliary reservoir, and an automatically controlled by-pass feed from said tank to said main reservoir.

7. In a carbureter, a casing forming a main reservoir, an auxiliary reservoir and a carbureting chamber, a fuel jet supplied from said main reservoir, a receiving tank communicating with a low level liquid supply, an overflow conduit from said tank to said auxiliary reservoir, means to subject said auxiliary reservoir to the pressure conditions in the motor intake, means to feed said main reservoir from said auxiliary reservoir and an automatically controlled by-pass feed from said tank to said main reservoir.

8. In a carbureter, a casing forming a main reservoir, an auxiliary reservoir and a carbureting chamber, a fuel jet supplied from said main reservoir, a receiving tank communicating with a low level liquid supply, an overflow conduit from said tank to said auxiliary reservoir, means to subject said auxiliary reservoir to the pressure of the motor intake, means to feed liquid fuel from said auxiliary reservoir to said main reservoir, means normally inoperative for feeding fuel direct from said tank to said main reservoir, and means rendered operative by a fall in the liquid level in the main reservoir for bringing said normally inoperative means into operation to feed said main reservoir.

9. In a carbureter, a casing forming a main reservoir, an auxiliary reservoir and a carbureting chamber, a fuel jet supplied from said main reservoir, a receiving tank communicating with a low level liquid supply, an overflow conduit from said tank to said auxiliary reservoir, means to subject said auxiliary reservoir to the pressure of the motor intake, means to feed liquid fuel from said auxiliary reservoir to said main reservoir, a by-pass feed from said

tank, around said auxiliary reservoir, to said main reservoir; and a float controlled valve for controlling said by-pass.

10. In a carbureter, a casing forming a main reservoir, an auxiliary reservoir and a carbureting chamber, a fuel jet supplied from said main reservoir, a receiving tank communicating with a low level liquid supply, an overflow conduit from said tank to said auxiliary reservoir, means to subject said auxiliary reservoir to the pressure of the motor intake, means to feed liquid fuel from said auxiliary reservoir to said main reservoir, a by-pass forming a communication between the main reservoir and a point in said tank below the mouth of said overflow conduit, a float, and a valve for said by-pass under the control of said float.
11. In a carbureter, a casing forming a main reservoir and a carbureting chamber, a fuel jet supplied from said main reservoir, a receiving tank for the liquid fuel supply, means independently operative for replenishing said main reservoir from said tank, and means rendering one of said replenish-

ing means ineffective while the other is in operation.

12. In a carbureter, a casing forming a main reservoir and a carbureting chamber, a fuel jet supplied from said main reservoir, a receiving tank for the liquid fuel supply, a normally operative means for feeding liquid fuel to said main reservoir from said tank, and a normally inoperative means for controlling a liquid fuel feed to said main reservoir from said tank.

13. In a carbureter, a casing forming a main reservoir and a carbureting chamber, a fuel jet supplied from said main reservoir, a receiving tank for the liquid fuel supply, a normally operative means for feeding liquid fuel to said main reservoir from said tank, a normally inoperative means for controlling a liquid fuel feed to said main reservoir from said tank, and means for rendering said normally inoperative means operative under abnormal conditions.

In testimony whereof, I have hereunto signed my name.

ALFRED WEILAND.
